UNITED STATES PATENT OFFICE.

CLYDE C. PALMER, OF SENATH, MISSOURI, ASSIGNOR OF ONE-HALF TO OLIVER C. SPARKS, OF KENNEDY, MISSOURI.

CLEANER'S SAFETY SPOTTING-CUP.

1,098,524.

Specification of Letters Patent. Patented June 2, 1914.

Application filed March 8, 1912. Serial No. 682,522.

To all whom it may concern:

Be it known that I, CLYDE C. PALMER, a citizen of the United States, residing at Senath, in the county of Dunklin, State of Missouri, have invented certain new and useful Improvements in Cleaners' Safety Spotting-Cups; and I do hereby declare the following to be a full, clear, and exact description of the invention, such as will enable others skilled in the art to which it appertains to make and use the same.

This invention relates to an improved safety spotting cup adapted for use by cleaners or in laundries or shoe-shining parlors.

Primarily, the object of the invention is to provide a very simple cup of this character adapted to contain the cleaning fluid and to close the same against the exposure to the atmosphere and yet permit convenient application of a tampion for saturating the latter in applying said cleaning fluid to the garments or other articles to be cleaned.

Another important object of the invention, is to provide a novel valve structure rendering the fluid readily accessible by the tampion and insuring of the full use of the fluid contained in the cup.

With the above and other objects in view, the invention consists in the combinations and arrangements of parts to be hereinafter more fully described, claimed and illustrated in the accompanying drawings, in which—

Figure 1 is a vertical sectional view of my improved safety spotting cup for cleaners. Fig. 2 is a similar view but showing the valve depressed as when inserting the tampion therein.

Referring more specifically to the drawings, wherein like reference characters designate similar parts throughout the several views, 10 designates a cup which is preferably formed of metal and is provided with a top 11 provided with a screw threaded nipple 12 for supplying cleaning fluid to the cup, while said nipple 12 is closed by a top 13 after the cup is filled. The cup is further provided with a bottom 14 which is spaced from the lower edge of the cup proper as shown and inclined toward the central portion of the cup in concaved form or approximately so, the said top and bottom being provided with central vertical registering openings. Connecting within

said openings is a vertical tube 15, the same terminating at the top portion and having its open upper end surrounded by a mouth-piece or collar 16 which is enlarged relative thereto and adapted for the insertion of a tampion 17 therein when it is desired to saturate the latter with the cleaning fluid. This tampion consists of a piece of rolled cloth suitably stitched together and is adapted to be saturated with the cleaning fluid for applying the same to the garment or articles to be cleaned, especially serving as a great convenience in removing grease spots or the like. The tube 15 is also provided with a plurality of peripherally spaced slots 18 which terminate short of the top portion of the cup but which at their lower ends extend to the bottom 14 so that the cleaning fluid will completely drain from within the cup and thereby insure of its economical use.

The lower end of the tube 15 extends considerably below the bottom 14 and is exteriorly threaded to receive a closure cap 19 the same maintaining an expansible coiled spring 20 therein, said spring carrying on its upper end a plunger 21 which has its bottom surface recessed as shown at 22 to provide a peripheral flange for retaining the spring in operative engagement with the plunger whereby said spring will force said plunger upwardly and by reason of its convexed upper face 23 which will be moved into engagement with the inwardly extending flange 24 of the mouth-piece or collar 16, the upper end of the tube will be closed.

By this construction, the splashing of the cleaning fluid will be prevented while the convexity of the plunger at its upper side permits convenient depression thereof by the tampion so that the tampion will only engage a very small portion of the plunger thereby exposing the greater portion of its end for saturation and this convex surface also insures thorough draining of the plunger before it moves to a closed position, thus preventing spilling of the cleaning fluid which is also assisted by the mouth piece or collar 16. This latter action is desirable owing to the fact that when the plunger is forced downwardly, the cleaning fluid is forced through the slots 18 and upon the plunger within the tube 15 and if the cup is nearly full, said mouth-piece will receive a portion of the cleaning fluid. It will also be apparent that only one hand is

necessary for properly using the tampon, thus avoiding the necessity of using two hands as is now generally done with the use of a bottle or the like, it being obvious that 5 the device can be used by garment cleaners, hat cleaners, laundrymen and also in shoe-shining parlors and various other purposes. The slots 18 in the tube or vertical opening are maintained to be better than openings 10 drilled or punched in the tube inasmuch as they let the gasoline or cleaning compound flow into and out of the tube more freely.

I claim:

15 A cleaner's receptacle for cleaning fluid including a can having a dished bottom disposed above the lower edge of the side wall, a dauber receiving tube disposed axially in

said can and having longitudinal slots in the sides extending to said bottom, there being an extension of said tube below said bottom 20 and having external screw threads, a cap threaded on to said extension, a spring supported by said cap, and a closure carried on the end of said spring and normally held by the latter in position to close the entrance 25 of said tube said spring and closure being adapted to be removed through said extension.

In testimony whereof, I affix my signature, in presence of two witnesses.

CLYDE C. PALMER.
